Patented Dec. 12, 1922.

Inventor

B. J. Long

By *W. E. Dunstan*,
his Attorney

UNITED STATES PATENT OFFICE.

BENJAMIN J. LONG, OF LAKewood, OHIO.

METHOD OF AND MEANS FOR PRODUCING STUCCO COLUMNS.

Application filed February 1, 1922. Serial No. 533,452.

To all whom it may concern:

Be it known that I, BENJAMIN J. LONG, a citizen of the United States, residing at Lakewood, in the county of Cuyahoga and 5 State of Ohio, have invented certain new and useful Improvements in Methods of and Means for Producing Stucco Columns, of which the following is a specification.

This invention relates to a method of and 10 means for producing stucco columns and has for its principal object to provide a method for producing stucco columns and the like of various diameters and entasis in a simple and inexpensive manner, and to a device for accomplishing the same.

With the above and other objects in view as will be readily understood, the invention will be hereinafter fully described, reference being had to the accompanying drawings, 20 and the novel features thereof will be distinctly pointed out in the appended claims.

In the drawings similar characters of reference are used to designate corresponding parts.

25 Figure 1 is a side elevation of a machine for producing stucco columns in accordance with my invention,

Fig. 2 is an end view of the machine,

Fig. 3 is a cross sectional view illustrating 30 the means for adjusting the guide rails,

Fig. 4 is a longitudinal sectional view illustrating the same mechanism as Fig. 3,

Fig. 5 illustrates the scraper as used upon the guide rails,

35 Fig. 6 illustrates a stucco column made in accordance with this invention, and

Fig. 7 is a cross sectional view taken on line 7—7 of Fig. 6.

In producing columns of plastic material 40 in accordance with my invention, a sheet of absorbent paper is wrapped upon a cylindrical form between annular flanges thereon and over the sheet of paper is wound wire in the form of a coil extending from one end 45 to the other and then back upon itself as said cylindrical form revolves. As said coil of wire revolves a layer of plastic material is spread upon the same to conform to a guide for thickness and longitudinal curva- 50 ture, then a wire is wound in the form of a coil over said layer of plastic material from end to end thereon and back upon itself, and then a layer of plastic material is spread over the second mentioned coil of wire in con- 55 formance with a guide for determining the

thickness and longitudinal curvature thereof to give a predetermined entasis to the column. The column is brought to a standstill and allowed to set, and when set is removed from said cylindrical form. 60

Any means for producing a column of plastic material in the manner described may be employed. A device of simple construction for accomplishing said purpose as illus- 65

trated in the drawings, consists of a frame comprising a head end 1 and a similar foot end 2, which are supported by pairs of legs 3 and 4. A shelf 5 is carried by angular iron bars 6 and 7 which are fixed to said legs, and said shelf serves to brace said legs in 70

their upright position. Each of the ends 1 and 2 is provided with a central bearing 8 and 9 for rotatably supporting a shaft 10 to which is fixed a cylindrical form 11, prefer- 75

ably of any suitable collapsible type. To this cylindrical form are fixed removable annular flanges 12 and 13 of any suitable design. Shaft 10 is rotated in any suitable manner, as for instance by means of a driving belt 80

passing around any of the different diameter pulleys indicated by 16. Said shaft with the cylindrical form thereon may be lifted from its bearings 8 and 9 after the bearing caps 14 and 15 have been removed.

The ends 1 and 2 are provided at each side 85 of their bearings 8 and 9 with horizontal flat surfaces 17 and 18 and vertical faces 19 and 20. Pairs of spaced angle bars at 21 and 22 are slidably supported upon the horizontal 90

flat surfaces 17 and 18 of the ends 1 and 2, and in the spaces between said pairs of angle bars are vertical adjustment rods 23 and 24 for carrying guide rails 25 and 26 for a strip 95

27 which is used as a scraper as will be hereinafter explained. The pairs of angle bars 21 and 22 are moved toward and away from the longitudinal center of the machine by means of adjusting screws 28 and 29 which are rotatably mounted in said pairs of angle 100

bars with collars 30 and 31 at each side thereof and a separate collar 32 therebetween. Said adjusting screws are threaded in the openings as 33 in the vertical faces 19 and 20 of the ends 1 and 2 and are provided with a hand-wheel 34 for convenience in 105

turning the same. The adjusting rods 23 and 24 are adapted to be moved and set at various elevations in the pairs of angle bars 21 and 22 by means of pairs of wing-nuts 35 and 36, which are mounted upon said adjust- 110

ing rods and engage washers 37 and 38 above and below said pairs of angle bars. The upper ends of the adjustment rods 23 and 24 are provided with rounded heads 39, 5 which are adapted to be moved longitudinally in suitable groove in each of the guide rails 25 and 26. The construction described allows for setting the guide rails nearer or further apart and at various elevations and 10 different longitudinal curvatures, or portions of the same straight and other portions curved or inclined.

To produce a stucco column in accordance with my invention by the means described, a suitable cylindrical form as 11 with the annular flanges 12 and 13 arranged thereon the proper distance apart is selected, and the shaft 10 carrying said cylindrical form is placed in the bearings 8 and 9. The 15 guide rails 25 and 26 are adjusted as to distance apart by means of the adjusting screws 28 and 29, and as to height and longitudinal curvature by means of the pairs of wing-nuts 35 and 36, for applying the first thickness of plastic material upon the cylindrical form 11, all as hereinbefore described. A sheet of absorbent paper 41 is wrapped upon the cylindrical form 11 between the angular flanges 12 and 13, and then a wire 42 is 20 wound over the sheet of paper in the form of a coil extending from end to end and then back upon itself as said cylindrical form is revolved. Next a layer of suitable plastic material 43 is applied over the coiled wire 25 of a greater thickness than desired and above the guide rails 25 and 26, which surplus thickness is removed by manually operating the scraper 27 upon said guide rails as the cylindrical form revolves. Said scraper is 30 preferably held at an angle, as illustrated in Fig. 5, and moved transversely upon the guide rails as it is advanced thereon. The guide rails 25 and 26 are again adjusted to a height and longitudinal curvature corresponding to the thickness of a second layer 35 of plastic material and the entasis of the column to be produced by means of the pairs of wing-nuts 35 and 36, as already described. A second coil of wire 44 is wound over the 40 layer of plastic material 43 in the same manner as the wire 42, then a second layer of plastic material 45 is applied to the same greater in thickness than desired and above the last adjusted positions of the guide rails 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

plastic material which consists in applying absorbent material over a revolving form, winding wire around the absorbent material, applying plastic material over the wire, and removing a portion of the plastic material.

2. The method of producing a column of plastic material which consists in applying absorbent material over a revolving form, winding wire around the absorbent material, applying plastic material over the wire, and removing a portion of the plastic material according to a fixed guide.

3. The method of producing a column of plastic material which consists in applying absorbent material over a revolving form, winding wire around the absorbent material, applying plastic material over the wire, and removing a portion of the plastic material by actuating a strip transversely and longitudinally to the axis of revolution.

4. The method of producing a column of plastic material which consists in applying absorbent material over a revolving form, winding wire around the absorbent material, applying plastic material over the wire and removing a portion of the plastic material by actuating a strip transversely and longitudinally to the axis of revolution upon guides at each side thereof.

5. The method of producing a column of plastic material which consists in applying absorbent material over a revolving form, winding wire around the absorbent material, applying plastic material over the wire and removing a portion of the plastic material by actuating a strip transversely and longitudinally to the axis of revolution upon guides at each side thereof for giving a predetermined size and entasis to the column.

6. The method of producing a column of plastic material which consists in wrapping a sheet of absorbent paper over a revolving form, winding wire around the sheet of paper, applying plastic material over the wire, and removing a portion of the plastic material.

7. In a means for producing a column of plastic material, the combination of a frame, a form rotatably supported in the frame, a guide for a means for removing a portion of the plastic material applied to said form for producing a column, the guide being arranged longitudinally of the form, means for adjusting the guide transversely and means for adjusting the guide vertically, substantially as described.

8. In a means for producing a column of plastic material, the combination of a frame, a form rotatably supported in the frame, a guide for a means for removing a portion of the plastic material applied to said form for producing a column, the guide being arranged longitudinally of the form and being flexible in its longitudinal direction,

65 1. The method of producing a column of

and means for adjusting different portions of the guide vertically, substantially as described.

9. In a means for producing columns of plastic material, the combination of a frame, a shaft rotatably supported by the frame, a form fixed upon the shaft, and a guide at each side of the form for a means adapted to be actuated thereon for removing a portion of the plastic material applied to said form for producing the column, substantially as described.

10. In a means for producing columns of plastic material, the combination of a frame, a shaft rotatably supported by the frame, a form fixed upon the shaft, means supported by the frame at each side of said form and slidable transversely toward and away therefrom, means for actuating said slidable means, rods carried by said slidable means, means for adjusting said

rods vertically, guides connected to said rods, and the guides being flexible in their longitudinal direction, substantially as described.

25

11. In a means for producing columns of plastic material, the combination of a frame, a shaft rotatably supported by the frame, a form fixed upon the shaft, means supported by the frame at each side of said form and slidable transversely toward and away therefrom, means for actuating said slidable means, rods carried by said slid- 30
able means, guides slidably connected in their longitudinal direction to said rods at each side of said form, the guides being flexible in their longitudinal directions, and means for adjusting said rods vertically and at different positions in said slidable means, sub- 35
stantially as described.

40

In testimony whereof I affix my signature.
BENJAMIN J. LONG.
